UNITED STATES PATENT OFFICE.

ALEXANDER C. DELSON, OF CHICAGO, ILLINOIS.

DESIGN FOR A NECK OR CHEST PROTECTOR.

42,082.

Specification for Design.

Patented Jan. 9, 1912.

Application filed October 26, 1910. Serial No. 589,265. Term of patent 7 years.

To all whom it may concern:

Be it known that I, ALEXANDER C. DELSON, a citizen of the United States, and residing in Chicago, in the county of Cook and the State of Illinois, have invented a new, original, and ornamental Design for Neck or Chest Protectors, of which the following is the specification, reference being had to the accompanying drawings, forming a part thereof.

In the drawings: Figure 1 is a front ele-

vation of a neck or chest protector showing my design. Fig. 2 is a fragmentary view of one of the ends of my design showing the stitch employed.

I claim—

The ornamental design for a "neck or chest protector" as shown.

ALEXANDER C. DELSON.
